UNITED STATES PATENT OFFICE.

HENRY ZAKRZEWSKI, OF CHICAGO, ILLINOIS, ASSIGNOR OF ONE-THIRD TO ANDREW KRAWCYNISKI AND ONE-THIRD TO JOHN A. KISIEL.

AUTOMATIC RAILWAY GATE.

1,409,636.

Specification of Letters Patent. Patented Mar. 14, 1922.

Application filed November 16, 1921. Serial No. 515,433.

To all whom it may concern:

Be it known that I, HENRY ZAKRZEWSKI, a citizen of the United States, residing at Chicago, in the county of Cook and State of Illinois, have invented certain new and useful Improvements in Automatic Railway Gates, of which the following is a specification.

This invention relates to gates adapted for use at railway and interurban crossings, to prevent pedestrians and drivers from injury by passing trains.

One of the primary purposes of the invention is to provide an automatically actuated gate adapted to be operated by an approaching train, to thereby automatically close the gates before the train reaches the crossing, and to automatically open them again when the train passes, thus obviating the necessity and expense of a crossing guard and removing the element of carelessness which is inevitably present where human watchfulness and manipulation are relied upon.

Another object of the invention is to provide an apparatus which will be accurate and reliable in operation, one which will be durable and not liable to get out of order, and one which can be economically manufactured and readily installed.

Other objects and advantages of the invention should be readily appreciated as the same becomes better understood, by reference to the following description, when considered in connection with the accompanying drawings.

Referring to the drawings:

Fig. 1 is a perspective view partially in section of an apparatus embodying my invention;

Fig. 2 is a fragmentary view showing one set of driving wheels and the position of the operating actuating blocks;

Fig. 3 is a fragmentary view showing an actuating block mounted on the locomotive and engaged with one of said wheels;

Fig. 4 is a sectional view on the line 4—4 of Fig. 1;

Fig. 5 is a view taken on the line 5—5 of Fig. 4;

Fig. 6 is a plan view of one set of driving wheels; and

Fig. 7 is a perspective view of one of the actuating blocks.

Referring to the drawings more in de-

tail, reference characters 8, 9, 11 and 12 indicate generally towers or housings on which the gates are mounted at each side of the road or crossing. Upon each of these posts, there is fixedly mounted upon a shaft 13, a main gate 14, which is substantially balanced by a counterweight 15, in proximity to this shaft and preferably beneath and a little at one side thereof, there is mounted at 16 an auxiliary gate 17 adapted to be disposed across the sidewalk in the path of pedestrians. The gates are shown in Fig. 1 of the drawings as being in down or closed position. It will be apparent from this figure that the short end 18 of the main gate overlies the short end 19 of the auxiliary gate, and when power is applied to the main gate to raise it from the horizontal position shown in full lines to an elevated or substantially vertical position, as shown in dotted lines, the end 18 will depress the end 19 of the auxiliary gate, thereby simultaneously swinging this gate to upright position, as shown. Upon reverse or downward movement of the main gate, the auxiliary gate will move correspondingly under the influence of gravity.

Upon each shaft 13, there is mounted a pulley 21, which is connected by a belt 22 with a pulley 23 mounted in the base of the tower and connected with a pulley 24, which in turn is actuated by a belt 25 from a pulley 26 disposed upon a countershaft 27 extending transversely of and beneath the tracks. Fragments of a double track road are shown in Fig. 1 of the drawings, one of the tracks being designated generally by reference character 28, and the other, by reference character 29.

Two pulleys 26 on the countershaft 27 are shown on an enlarged scale in Fig. 4, from which it will be observed that these pulleys have a common hub 31 mounted upon the shaft 27 and frictionally connected thereto by means of friction blocks 32 mounted in radially disposed sockets in the hub and urged into frictional engagement with the shaft by coiled expansion springs. The outer end of each socket is closed by a screw plug 34 by manipulation of which, the tension on the springs may be regulated. A yoke 35 is preferably employed to retain the pulleys against longitudinal displacement. This frictional connection between the pulleys 26 and the shaft 27 is provided

so that a slippage may occur at this point, and thereby prevent breakage of the parts when rotation of the shaft 27 is quickly begun.

- 5 In order to insure a positive drive between the pulleys 26 and their respective driven pulleys 24, each of these pulleys is preferably provided on its periphery with a series of sockets 36, and the belts 25 are provided
- 10 on their inner faces with correspondingly shaped projections or blocks 37 adapted to engage in the sockets 36, thereby insuring a positive driving connection between the pulleys 26 and the mechanism in each tower.
- 15 It is understood, of course, that a set of pulleys 26 is mounted at each end of the countershaft, as shown in Fig. 1 and that a driving connection such as above described, is provided between each of these
- 20 pulleys and the mechanism in its respective tower.

The shaft 27 is adapted to be actuated by a train approaching upon either track, and it is accordingly equipped near the center thereof with a pair of pulleys 38, each connected by a belt 39 with a driving pulley 41 mounted upon the inner end of a shaft 42 which is provided near its outer end with a driving wheel 43. This wheel and also a companion driving wheel 44, mounted in laterally offset relation to the wheel 43, and connected thereto by a crossed belt 45 is set beneath the track and either between or at one side of the rails and extends upwardly in position to be engaged and actuated by a grooved block carried by the train. Each of these wheels is equipped with a circumferential radially projecting flange 46 adapted to be frictionally engaged by the side walls of a groove 47 formed in the under-surface of a friction block 48, one of which blocks is mounted upon locomotive 49, as shown in Fig. 3, in alignment with the wheel 44, while a similar block is mounted upon the rear car of the train in alignment with and in position to engage the other wheel 43.

Assuming a train to be approaching the apparatus shown in Fig. 1 upon the track 50 28 from the right, the block 48 on the locomotive will engage the wheel 44, rotating this wheel in a counterclockwise direction and through the crossed belt 45, rotating shaft 42 in a clockwise direction. This movement will be transmitted through the belt 39 to the countershaft 27 and the pulleys 26, and from thence through the pulleys 23 and the belts 22 to the pulleys 21 by which the shafts 13 and the gates 14 carried thereby, are rotated to lower the gates. It will be apparent from Fig. 1 that the belts 22 at one side of the crossing are crossed, while those at the other side are straight, thereby causing the gate carrying shafts to rotate in opposite directions so

as to lower the main gates toward each other over the crossing. The gates will remain in lowered position until a similar block 48 carried by the rear car engages the driving wheel 43, whereupon all of the parts will be operated in the opposite direction to lift the gates as the rear end of the train passes the crossing.

The driving wheels 44 and 45 are, of course, mounted at any desirable distance 75 from the crossing; and the belts 39 will be made of the requisite length to accommodate the desired location of the driving wheels. Since the initial movement of the shaft 27 may be quite rapid if the train is 80 running at a high rate of speed, the frictional connection between this shaft and the pulleys 26 will permit a slippage until the momentum of the parts to be moved is overcome, thus preventing breakage of or injury 85 to the apparatus. All of the operating parts are set beneath the tracks in suitable casings 51, which are covered over to protect the operating mechanism, and may if desired, be set in concrete. The parts are all 90 housed against the weather and are therefore durable and not liable to get out of order. The positive drive afforded by the recessed pulleys and the cooperating belts provided with projecting blocks insures against 95 belt slippage and while in most cases, it may be necessary to employ these non-slip belts on the longer stretches only, it should be manifest that this type of belt may be employed throughout the apparatus if desired. 100

It is believed that my invention, its mode of operation, and many of its advantages will be understood from the foregoing without further description, and while I have shown and described a preferred embodiment of the invention, obviously the details of construction may be varied within wide limits without departing from the essence of the invention as defined in the following claims. 110

I claim:

1. In an automatic railway gate, the combination of a pair of driving wheels mounted in offset relation to each other and each provided with a circumferential friction flange, a pair of grooved friction members adapted to be carried at the front and rear respectively of a train in position to engage the flanges of their respective friction wheels and thereby rotate said wheels, a crossed belt 115 connecting said wheels, a countershaft, a non-slip belt connecting said wheels with said countershaft for rotating the same, a plurality of pivotally mounted gates, an intermediate shaft for each gate, a belt connecting each gate with its intermediate shaft, and a belt connecting each intermediate shaft with said countershaft, the driving connections between said driving wheels and said gates being so arranged that the gates are 130

lowered upon actuation of one wheel and raised upon actuation of the other wheel.

2. In an automatic railway gate, the combination of a pair of driving wheels mounted to be laterally engaged by grooved friction blocks carried at the front and rear respectively of a train, a plurality of pivotally mounted gates, and driving connections between said gates and said wheels including recessed pulleys and belts provided with projections engaging in said recesses to provide a positive driving connection whereby said gates are raised and lowered.

3. In an automatic railway gate, the combination of a plurality of main gates, a plurality of auxiliary gates adapted to be engaged and actuated by said main gates, and means for raising and lowering said main gates, said means comprising driving wheels mounted adjacent to the tracks, grooved friction blocks adapted to be carried by the

front and rear respectively of a train, and driving connections including belts and pulleys interposed between said driving wheels and said main gates.

25

4. In an automatic railway gate, the combination of a plurality of pairs of driving wheels mounted adjacent the tracks, friction blocks adapted to be carried by the front and rear of a train in position to respectively engage said wheels and rotate the same, a counter-shaft, a belt and pulley driving connection between each set of driving wheels and said countershaft, a plurality of towers located at each side of the tracks, main and auxiliary gates fulcrumed on said towers, and belt and pulley driving connections between said countershaft and said gates whereby the gates are raised and lowered upon actuation of said wheels.
